UNITED STATES PATENT OFFICE.

ORRELL ASHTON, OF SWAMPSCOTT, MASSACHUSETTS, ASSIGNOR TO UNITED SHOE MACHINERY COMPANY, OF PATERSON, NEW JERSEY, A CORPORATION OF NEW JERSEY.

GRIPPER-MECHANISM.

1,030,838.

Specification of Letters Patent. Patented June 25, 1912.

Original application filed August 2, 1907, Serial No. 386,799. Divided and this application filed March 9, 1911. Serial No. 613,325.

To all whom it may concern:

Be it known that I, ORRELL ASHTON, a citizen of the United States, residing at Swampscott, in the county of Essex and State of Massachusetts, have invented certain Improvements in Gripper Mechanisms, of which the following description, in connection with the accompanying drawings, is a specification, like reference characters 10 on the drawings indicating like parts in the several figures.

This invention relates to machines for use in the manufacture of boots and shoes and particularly to mechanism for working 15 an upper over a last.

The invention is herein shown as embodied in the upper pulling and holding mechanism of a pulling-over machine of the type shown in United States Letters Patent 20 No. 663,777, granted on the application of Ronald F. McFeely, but the invention is applicable also to other machines.

The mechanism in which the invention is herein shown as embodied comprises two 25 pairs of gripper jaws connected to a common actuator and arranged to engage adjacent portions of stock. In the pulling-over machine of which this illustrated mechanism forms a part one pair of gripper jaws engages one end of the portion or belt of upper which extends over the ball of the last and the other pair of jaws engages one end of a portion or belt of upper which is located farther forward on the 30 last and includes the toe tip seam in shoes which have a toe tip. This latter belt of upper is shorter than the former, and in an upper loosely applied to the last it fits more closely to the last than does the belt 35 at the ball of the shoe, because lasts are usually so formed that the upper has to be drawn down considerably to conform to the contour of the last over the ball. For these reasons, and because the toe tip seam, if 40 one is present in the upper, renders the belt of upper engaged by the forward gripper jaws less elastic than that engaged by the rear gripper jaws, the rear jaws require to have a greater range of pulling movement 45 than do the forward jaws.

One object of the invention is to provide

a connection between the two pairs of gripping jaws and their common actuator by which the rear pair of jaws may be given the required greater range of pulling movement without liability of excessively straining the belt of stock engaged by the forward pair of jaws. 55

To this end a feature of the invention consists in a grippers mechanism comprising a plurality of pairs of jaws and a connection between the pairs of jaws and a single actuator which will insure a greater movement to one pair of jaws than to the other pair. Preferably the connection will 60 be arranged to insure a predetermined extent of relative movement of the two pairs of jaws. This connection may include an adjustable member by which the extent of the relative movement may be varied. In 65 the embodiment shown the rear jaws are arranged to begin their movement in advance of the forward jaws and to continue through a predetermined distance before the forward jaws are similarly lifted. To 70 this end the rear jaws are connected with a lifting bar which has a lost motion connection with the forward jaws and through which the two pairs of jaws are moved together during the latter part of the pulling 75 movement of the gripper mechanism. Also in the embodiment of the invention shown the two pairs of gripper jaws are closed successively so that the rear jaws seize the upper and initially or partially pull it into 80 the usual depressed portion of the upper surface of the last at the ball. Then the forward jaws close and the two pairs of jaws rise together to complete the straining 85 of the upper into conformity with the shape 90 of the last.

These and other features of the invention will be more fully explained in the following description and then pointed out in the claims.

The drawings represent a preferred embodiment of the invention applied to a pulling-over machine of substantially the general construction shown in said United States Letters Patent No. 663,777. 95

Figure 1 is a side elevation of the grippers partly in section; Fig. 2 is a section

on line 6—6 of Fig. 1; Fig. 3 is a section on line 7—7 of Fig. 1; Fig. 4 is a section on line 8—8 of Fig. 2; Fig. 5 is a detail view of a modification taken in the same plane as Fig. 2.

The frame 2, which may be the frame of the pulling-over machine shown in said Letters Patent No. 663,777, supports levers 4 that are fulcrumed at 5 and from which 10 are suspended bars 6. There are in the machine sets of grippers for engaging the upper at opposite sides of the last which is held from displacement by a sole rest while the upper is being pulled. A set of these 15 grippers is illustrated in Fig. 1 and comprises a plurality of pairs of jaws connected through casings 8 and 9 with the one operating bar 6. One jaw 10 of each pair of jaws is pivotally connected to its casing 20 while the other jaw 11 of each pair is rigidly attached to the casing which is shaped to receive it between two edge plates 12, the adjacent faces of which may be corrugated to fit similar corrugations on 25 the edges of the jaw. The jaw is clamped between the edge plates by a connecting member 14, shown best in Fig. 4, which has a conical head fitting a similarly shaped recess in one edge plate. It also has screw 30 threaded engagement with a tapering locking member 15 that is split at 16 so that it will be contracted and locked upon the holding member as it is drawn into its conical recess in the casing.

35 The construction thus far described is not a part of the present invention.

The gripping faces of each of the jaws 10 and 11 are formed by alternate teeth or ribs 20 and plane faces 22 which are so arranged in the assembled grippers that the teeth or ribs on the jaw 10 will be opposed to the plane faces on the jaw 11 and the teeth or ribs on the jaw 11 will bite or indent the stock against the plane faces on the 45 jaw 10. The lower tooth or rib 25 of the jaw 10, which engages the outer side of the upper leather, is rounded or blunt so that it will not scrape or scar the upper as the stock pulls out when the jaws release their 50 grip upon the upper. Each casing contains a gripper controller 30 through which the jaw 10 is first rocked to grip the stock and then, when it can rock no farther, the two jaws are uplifted to pull the stock. For 55 this purpose the controller has a roller 32 which engages the inclined rear face of the upper arm of jaw 10 as shown in Fig. 2, which is a section through the casing 8 and the forward pair of jaws. The other controller is the same. A cross bar 35 is secured to the controller for the rear pair of jaws and extends across to the other controller where it is received between ledges 36 on

the outer side of the controller. The cross bar is notched to provide a narrow portion 65 forming a lost motion connection with the controller for the forward jaw. The operating bar has a depending hook 38 which engages the middle portion of the cross bar and through which the controlling devices 70 are lifted for closing and then raising the jaws. By reason of the lost motion connection the rear jaws are closed and raised to pull the upper about the ball of the last to a predetermined extent before the forward 75 jaws are closed and raised to pull the upper in the region of the toe tip seam. If desired, the extent of the relative movement of the pairs of jaws may be adjustably varied, as, for example, by providing the 80 reduced portion of the cross bar 35 with an adjustable contact member 39, as shown in Fig. 5. Each of the jaws of the rear pair of jaws 10 has a rearward extension, as shown in Fig. 1, which presents, with the 85 shank of the jaw an L shape, by which the gripping faces are carried backwardly to a width substantially greater than it is desirable to make the shanks of the jaws.

In the use of the invention in the form 90 in which it is shown as embodied, a shoe is presented with the bottom against the sole rest and the upper between the jaws of the open grippers. The operating bars are then raised. The first effect is to close the rear 95 jaws which engage the ball of upper extending about the last at the base of the instep and back of the position of the toe tip seam. As soon as these jaws are closed they are uplifted and pull the upper about this portion of the last. When these jaws have 100 moved through a predetermined distance governed by the extent of lost motion between the cross bar 35 and the ledges 36, and have initially pulled the upper back 105 of the toe tip seam, then the forward pair of jaws is closed and thereafter uplifted to pull the upper in the region of the tip seam. The last supporters of the machine then move inwardly and set the side clamps 110 against the sides of the last below the plane of the last bottom to grip the upper and prevent it from slipping back. The tack arms next swing inwardly, releasing the grippers which retire as the arms advance. The pressers reach the edge of the last 115 after the grippers are released and move over the edge and bottom of the last as the arms swing inwardly, wiping over the upper that was between the pairs of jaws and pressing the upper against the innersole into position to receive the fastening tacks, which are then driven, after which the parts may 120 return to starting position. It will of course be understood that while for the purpose of 125 explanation this invention is here shown as

applied to the machine of said Letters Patent No. 663,777 for which it was especially devised, it may also be used in other machines.

5 This application is a division of my application, Serial No. 386,799, filed August 2, 1907, upon which Letters Patent No. 1,007,766 was granted, November 7, 1911.

Having described my invention, what I 10 claim as new and desire to secure by Letters Patent of the United States is:—

1. In a mechanism of the class described, pairs of gripper jaws and actuating mechanism for causing the jaws to engage and pull adjacent portions of stock, said actuating mechanism being constructed and arranged to impart to said jaws predetermined relative movements for pulling the portions of stock engaged by them to different 20 extents.

2. In a mechanism of the class described, pairs of gripper jaws for engaging adjacent portions of stock, and an actuating mechanism common to said pairs of jaws and constructed and arranged to cause one of said pairs of jaws to be actuated in advance of the other pair for pulling the stock.

3. In a mechanism of the class described, pairs of gripper jaws for engaging adjacent portions of stock, and an actuating mechanism common to said pairs of jaws and constructed and arranged to insure a predetermined movement of one pair of jaws for stretching the stock before the other pair of 35 jaws pulls the stock.

4. In a mechanism of the class described, pairs of gripper jaws for engaging and pulling adjacent portions of stock, and actuating mechanism connected with both pairs of 40 jaws and constructed and arranged normally to lift one pair of jaws in advance of the other pair.

5. In a mechanism of the class described, pairs of gripper jaws for engaging and pulling adjacent portions of stock, and actuating mechanism connected with both pairs of jaws and constructed and arranged normally to close and lift the pairs of jaws 45 successively.

50 6. In a mechanism of the class described, pairs of gripper jaws for engaging adjacent portions of stock and actuating mechanism constructed and arranged to close the pairs of jaws successively and then impart to one of said jaws a pulling movement differing to a predetermined extent from the pulling movement imparted to the other pair of jaws.

7. In a mechanism of the class described, 60 pairs of gripper jaws for embracing adjacent portions of stock, and actuating mechanism constructed and arranged to move one pair of jaws through a predetermined

distance and then to begin to move the other pair of jaws.

8. In a mechanism of the class described, pairs of gripper jaws for embracing adjacent portions of stock; and actuating mechanism constructed and arranged to cause in predetermined order one pair of jaws to 70 grip and partially pull the upper while an adjacent pair of jaws remains open and then to close the second pair of jaws and move it with the first-mentioned pair.

9. In a mechanism of the class described, 75 pairs of gripper jaws for engaging adjacent portions of stock, and actuating mechanism comprising a direct connection with one pair of jaws and a lost motion connection with another pair of jaws.

10. In a machine of the class described, gripper jaws for engaging a portion of upper extending over the ball of the last and gripper jaws for engaging a portion of upper extending over the forward portion of 85 the last in the region of the toe tip seam, combined with actuating mechanism constructed and arranged to uplift the jaws for straining the upper over the ball of the last before it is strained by the other gripper 90 jaws.

11. In a machine of the class described, gripper jaws for engaging and pulling a belt of upper extending about the last in the region of the toe tip seam and gripper jaws 95 for engaging and pulling a belt of upper extending about the last in the rear of the toe tip seam, means for actuating the jaws to seize the two belts of upper successively, and means for actuating the rear jaws before the other jaws for straining the upper.

12. In a machine of the class described, the combination with the operating bar 6 and the gripper carriers 8, 9, of two pairs of gripper jaws, the controllers 30 for each 105 pair, and the cross bar 35 secured to one controller and extending across to the other controller and having a lost motion connection with said other controller for the purpose described.

13. In a machine of the class described, the combination with the operating bar 6 and the gripper carriers 8, 9, of two pairs of gripper jaws, the controllers 30 for each 115 pair, and the cross bar 35 secured to one controller and extending across to the other controller and having a lost motion connection with said other controller for lifting said two pairs of jaws different distances, and the abutment 2, coöperating with the gripper carriers and the operating bar 6 to restore the grippers to predetermined relative vertical positions for seizing the next upper.

14. In a machine of the class described, 125 the combination with the operating bar 6

and the gripper carriers 8, 9, of two pairs of gripper jaws, the controllers 30 for each pair, and the cross bar 35 secured to one controller and extending laterally, ledges 36 on 5 the other controller between which said cross bar is received and an adjustable contact member 39 carried on the cross bar for engaging the ledges.

In testimony whereof I have signed my name to this specification in the presence of 10 two subscribing witnesses.

ORRELL ASHTON.
